UNITED STATES PATENT OFFICE.

JOHN G. DIXON, OF NEW YORK, N. Y., ASSIGNOR OF ONE-HALF TO HERMANN WILCK, OF SAME PLACE.

COLLAR AND CUFF DRYING APPARATUS.

SPECIFICATION forming part of Letters Patent No. 431,766, dated July 8, 1890.

Application filed November 10, 1887. Serial No. 254,843. (No model.)

To all whom it may concern:

Be it known that I, JOHN G. DIXON, a citizen of the United States of America, residing in New York city, State of New York, have invented a new and useful Drying-Machine, of which the following is a specification.

My invention relates to an improvement in apparatus for drying collars and cuffs, and has for its object to so bring currents of hot air in contact with the articles to be dried that no portion of such heated air shall be allowed to escape without bearing away its due proportion of moisture; also, to facilitate the handling of the goods undergoing the drying process, to dampen the said goods preparatory to ironing, and finally the economizing of heat and space by condensing the drying-chamber to the smallest dimensions.

The invention consists in the novel construction, arrangement, and combination of parts hereinafter fully set forth, and pointed out in the claims.

Reference is to be had to the accompanying drawings, forming a part of this specification, in which similar letters and figures of reference indicate corresponding parts in all the views.

Figure 1 is a longitudinal vertical section through the machine. Fig. 2 is a horizontal section above the tables. Fig. 3 is a transverse section on line $\alpha\alpha$ of Fig. 2. Fig. 4 is a side elevation of one end of the trams or supporting-rails. Fig. 5 is a plan view of the same. Fig. 6 is a transverse section on line yy of Fig. 1. Fig. 7 is a detail showing the carriers inclined for use in drying wool and like material.

In carrying out the invention the body of the device is adapted for use as a drying-apartment, and consists of an essentially-rectangular frame having a chimney at one upper end and provided with a series of horizontal spaced and parallel baffle-plates projected alternately from opposite ends, as illustrated in Fig. 1. By this means a hot-air-generating chamber 12 is formed in the bottom and an upwardly-winding hot-air passage or flue 13 leads from the lower chamber at a point α , which flue 13 terminates in the aforesaid chimney 11. The body is preferably

made of wood lined with any appropriate sheet metal; but the baffle-plates or partitions are made of sheet metal. The hot-air-generating chamber 12 is furnished with steam-pipes or other heating devices, and may be of any desired dimensions. Steam-pipes 35 are also placed on the plates forming the flue 13 throughout its length. The air passages or flues between the partitions forming the same should be very shallow—for instance, from six to eight inches—and of a width a little more than equal to the length of the carriers 16. I prefer the width to be between five and six feet. Near the front and rear ends of the body sprocket-wheels 17 are suitably journaled, around which are passed endless chains 18, which chains, entering a slot 19 in the chamber 12, pass upward through the flue 13, guided and supported by suitable pulleys 18^a, 70 journaled in the body opposite the ends of the deflecting-plates, and also below the entering-slot 19 and a slot 20 below the chimney, adapted as an exit for the chain.

In suitable perforated links of the propelling-chain the frames or open shelves 16 are pivoted on suitable bearings, which shelves or frames, for convenience, I call "carriers," and which are adapted to receive light gauze screens 21. The carriers 16 are provided on their ends at diagonally-opposite corners, as shown in Figs. 1 and 5, with small tram-wheels 22, revolving on spindles rigidly fixed to the frames in the position indicated in the drawings. The tram-wheels 22 are adapted to run upon tramways 23 and 23^a, placed inside and between the endless side propelling-chains 18. The lateral position of the tramways relative to the chains is maintained throughout; but the vertical position of the same is varied, so as to maintain the carriers 16 in any required position. This will be more fully explained farther on. It will be seen by reference to Figs. 1 and 5 that while the carriers are moving in a horizontal direction they are supported entirely by the tram-wheels running upon the tramways, which also prevent the propelling-chain from sagging. In ascending and descending, however, the weight of the carriers is partly upon the propelling-chain.

Starching-tables 24 are arranged on both

sides of the chains and carriers, as best shown in Fig. 2, from which the collars and cuffs are taken when properly prepared and placed upon the carriers. These opposite lines of 5 tables are connected to their frames by U-girders 24, which pass underneath the chains and carriers, and on which the tramway at this point rest. By this construction the carriers will be about on a level with the upper 10 surface of the tables to receive the trays, and their connecting-girders form the supports for tramways.

On the shaft connecting the main or driving sprocket-wheels a worm-wheel 25 is keyed, 15 which meshes with a worm upon a shaft 26, the said shaft being driven by a belt engaging the pulley 27. The driving-chain wheels above referred to are the only ones connected by a shaft. All the supporting wheels or pulleys 20 revolve independently of each other on spindles rigidly fixed in the side walls of the body, or, where situated outside the hot-air flues, to head-blocks or floor-hangers 28.

A series of atomizers 29 are placed over 25 and under the passing carriers, throwing spray from above and below, as indicated in Figs. 1 and 6, so as to dampen the collars and cuffs on both sides as they are borne past. The atomizers are supplied with water and either 30 compressed air or steam in any approved manner.

The tramways, when passing through the upper part of the hot-air-generating chamber and the air-flues, are supported upon 35 columns 30, and to the curved or switch ends of the tramways guard-rails 33 are connected and supported by plates 31, as shown in Figs. 4 and 5, or the tramways may be supported by brackets extending from the side walls of the 40 body or casing.

The body or casing containing the hot-air chamber and flue is represented as supported above the starching-tables by posts. In practice, however, the drying-chamber may be 45 better placed in a room on a floor above or suspended from the ceiling of the operating room, if more practicable.

The endless chains and the pivoted carrier frames carrying the screens, with the attached 50 tram-wheels running upon the tramways, when running horizontally, make up what might for convenience be called a "sectional" apron.

When it is desirable to hold the carriers 16 in the same horizontal plane, as in passing 55 the starching-tables, the tracks or tramways should be slightly under the level of the side chains, the exact distance to be determined by the size of the tram-wheels used. The trunnions or journals of the carriers, as will 60 be seen by reference to Fig. 5, extend across and above the tramways, and it is obvious that the chains cannot sink below the tramways nor the tramways rise above across the level of the chains without bringing about a 65 collision with the trunnions on which the carriers are pivoted.

As it is necessary that the chains should

cross one of the tramways in rounding the supporting-pulleys, (see Figs. 1 and 5,) I arrange the same so that whenever it is necessary to make a break or gap in one tramway 70 23 for the trunnion of the carrier to pass the opposite tramway shall at that point remain unbroken, so that whenever the tram-wheel running upon the tramway 23 is left without 75 a support then the diagonally-opposite tram-wheel running upon the tramway 23^a, which is unbroken at that point, and also provided with a guard-rail 33, holds the carrier in position. To illustrate this more clearly, I refer to Fig. 4, where I make a break in a tramway 23 just where it begins to curve upward at the point *b* sufficient to allow the trunnion to pass freely through. Thus, when the carrier 16, with its trunnion pivoted in the perforated link of the chain, arrives at the point *b*, the trunnion passes through the opening and moves around the periphery of the pulley, while the tram-wheel is lifted from the track 23 and passes upwardly without a guide 80 until it strikes the downwardly-curved end of the upper tramway at *b'*. While the tram is passing across the gap from the point *b* to point *c'* the carrier is held in place by the diagonally-opposite tram-wheel running upon the 85 opposite tramway 23^a, in which there is no break until it reaches the point *c*, by which time the first-mentioned tram running upon the tramway 23 has arrived at the point *c'*, 90 where it is engaged by the guide-block 34, 100 whereby the carrier is guided while the opposite tram is passing the gap *c*.

The guard-rails 33 are placed wherever the tramways curve as an additional precaution. As the journals upon which the carriers are 105 pivoted are less than one inch in diameter, the gaps will be sufficient if made about two inches in width.

It will be observed by reference to Fig. 1 that at the point where the driving sprocket-wheels are situated and where the chains and carriers begin to ascend no brake or gap in the tramway 23^a is required, as, owing to the inclination of the same, the trunnions of the ascending carriers clear the track and do 115 not need to pass through the same. That portion of the tramway that has been running horizontal, curves upward, and the ascending tramway, curving downward, laps by the curving end of the lower tramway, constituting the switch or guideway through 120 which the tram-wheel passes. A gap is, however, necessary in the tramway 23 at this point, as the trunnions of the carriers here passing or ascending from a horizontal to an 125 inclined position must of necessity pass through the track, as at other points. The arrangement of the tramways at the descending points of the chain and carriers is upon the same principle, only reversed.

The rate of speed which it is desired that the sectional apron or carriers should travel may be varied by means of the cone-pulley 27. If the articles are to be exposed to the 130

heat for the same length of time it is evident that the faster the apron travels the greater must be the length of the hot-air passages through which it travels. Thus if the apron travels at the rate of four feet per minute, and if it must be exposed to the heat twenty minutes in order to dry the articles, then the hot-air passages should be four by twenty or eighty feet long in all.

The manner of operating the machine is as follows: Collars and cuffs, after being properly prepared on the starching-tables, are placed by operatives on the gauze screens, which screens are preferably rested upon the tables while being filled. The screens are then laid upon the passing carriers, being secured from slipping by small flanges on their under side, which flanges extend downward and fit into the inner side of the carrier-frames. As the carriers pass slowly in the direction indicated by arrows, Fig. 1, the screens filled with the collars and cuffs are carried past the driving-chain or sprocket-wheels, and thence, ascending, enter the hot-air chamber 12 through the slot 19, after traversing which they pass, as shown in Fig. 1, into the hot-air flue 13 at the point *a*, and finally emerge, fully dried, through a slot 20. Thence they descend and pass through the spray from atomizers, and are removed from the screens at the rear pulleys. The now empty screens are allowed to remain on the carriers until they arrive opposite to the operating-tables, where they are lifted off and filled screens put in their place.

Whenever it is not desirable to dampen the article being dried, the atomizers may be shut off by closing the valves in the water and steam pipes leading thereto.

Should the machine be used for drying wool or other fibrous substances, it would be advantageous to pass the carriers through the hot-air passages in a tilted position, as shown in Fig. 7, to which I refer for the arrangement of the tramways necessary to produce this result. As the tilted carriers with their loaded screens would more nearly fill the hot-air flues, the hot air would have to pass through the fibrous substance in process of drying, the advantage of which will be evident. If necessary to increase the hot-air current, an exhaust-fan may be placed in the chimney 11. It will be observed that the flue 13 is just sufficiently deep to allow the carriers and chains to pass, which is a decided advantage in a drier, creating a current of hot air and bringing the hot air in decided contact with the articles to be dried; and it will also be apparent that as the closely-approaching metallic plate or partitions which form the shallow hot-air flue absorb heat from the steam-pipe 35, resting upon them, they in

turn give out and from their proximity to each other subject the closely-passing collars and cuffs to their radiant heat.

I am aware that carriers adapted to bear screens suspended from endless side chains and kept in a horizontal position by gravity have been used heretofore in driers; also, that gauze screens have been used in connection therewith. I am also aware that partitions in drying-rooms have been used to form air-passages and for deflecting currents of hot air. I therefore do not claim such appliances, broadly.

Having thus fully described my invention, what I claim as new, and desire to secure by Letters Patent, is—

1. The combination, with a receptacle provided with a heat-generating chamber at the lower side and a chimney upon the opposite side and a series of closely-approaching deflecting-plates within the receptacle projected from opposite ends, forming a winding flue connecting the chimney and heating-chamber, of a series of winding tramways having gaps alternately at their bends, substantially as described, supported within the heating-chamber and winding flue, endless chains traversing the receptacle contiguous to the tramways, carriers pivoted to said chains, and tram-wheels pivoted to opposite diagonal corners of the carriers traveling upon said tramways, substantially as and for the purpose specified.

2. The combination, with the drying-chamber having inlet and outlet opening in its ends, of U-shaped girders, tramways resting on said girders and extending through the drying-chamber, and endless chains passing through and below said chamber and having carriers provided with tram-wheels traveling on said tramways, and the sprocket-wheels for said chains, substantially as set forth.

3. The combination, with the drying-chamber having opposite inlet and outlet apertures, sprocket-wheels, and the longitudinally-extending tramways below the drying-chamber and extending beyond the ends thereof around the sprocket-wheels and through the said chamber, said tramways having alternating gaps and guard-rails at their bends, of the endless chains passing around the sprocket-wheels and following the line of the tramways within and below the drying-chamber, and the tray-receiving carriers pivoted between the chains and having diagonally-opposite wheels running on the tramways, substantially as set forth.

JOHN G. DIXON.
